UNITED STATES PATENT OFFICE.

HARRIS G. PARR, OF FORT WORTH, TEXAS, ASSIGNOR TO FORT WORTH WELL MACHINERY & SUPPLY CO., OF FORT WORTH, TEXAS, A CORPORATION OF TEXAS.

WELL-DRILLING MACHINE.

Application filed March 20, 1923. Serial No. 626,256.

My invention relates to well drilling machines and more particularly to a combination spudding mechanism and walking beam; and the object is to provide in one machine a spudder and a walking beam, either one of which may be used for drilling purposes, thus making a machine which has a dual capacity. The object is to improve such machines as are illustrated in Patent No. 1,440,889, dated Jan. 2, 1923, by providing walking beam attachments on the same frame.

Other objects and advantages will be fully explained in the following description and the invention will be more particularly pointed out in the claims.

Reference is had to the accompanying drawings which form a part of this application.

Fig. 1 is a side elevation of the machine equipped with the walking beam and attachments, a part of the spudder mechanism being omitted. Fig. 2 is a plan view of the same, Fig. 3 is a vertical section taken on the line 3—3 of Fig. 1. Fig. 4 is a side elevation of the machine showing both the spudder attachments and the walking beam attachments, the walking beam and attachments being shown in inoperative form when the machine is using the spudder attachments. Fig. 5 is a detail view, showing the adjustability of the pitman bars of the walking beam attachment.

Fig. 6 is a broken front end view, showing the manner of pivotally connecting the derrick to the frame.

Similar characters of reference are used to indicate the same parts throughout the several views.

The machine is provided with the usual base frame members 1 and 2 with uprights 3 and 4 and cross brace 29 and pivot bar 6 which serves as a cross-bar. The spudding frame members 7 are pivotally mounted on the bar 6. There is no change in the spudding frame members 7, cross-beam 8, and knuckle joint 9. An upright 10 is attached to the cross frame member 2 and made rigid by means of braces 11 and 12 attached thereto and to the frame members 1 and 4 respectively. The walking beam is formed of two beams 13 arranged in the form of the capital A. A fulcrum 14 is provided for the walking beam and the bars 13 are connected to the fulcrum by underslung attach-

ments. The fulcrum 14 is mounted in the upright 10 and two pairs of U-bolts 15 are mounted on the fulcrum bar 14 and projected down past the bars 13 and through plates 16 and secured in the plates 16 by nuts 17. At the operating end, the walking beam is provided with a guide shoe 18 for engaging the temper screw suspension chain. The bars 13 are attached rigidly to the guide shoe 18 and the chain is wrapped on the end of the walking beam and extended down the groove in the shoe and attached to the temper screw. The walking beam members 13 are operated by pitman bars 20 which are pivotally connected to cranks 21 which are rigid with shaft 22. The pitman rods or bars 20 are pivotally connected to the pivot shaft 23 and bearings 24 are provided for the shaft 23. Plates 25 are attached to the pitman bars 20 and pivotally connected to the bearings 24 by means of pivot pins 32 so that the pitman bars 20 can be swung outwardly as shown by dotted outline in Fig. 3 and then to the position shown in Fig. 4 when they are not in use and while the spudding beams are at work. The walking beam members 13 are connected to the shaft 23 by U-bolts 26. The pulley or wheel 27 is rigid with the shaft 22 for driving this shaft and the wheel can be driven by any suitable power.

The uprights 4 are inclined forward so that the derrick 28 may be inclined far enough to bring the drilling tools vertically over the well. The uprights 4 are braced by cross-beam 2, longitudinal frame members 1, and by a cross frame member 29. The derrick 28 is pivotally mounted on the pivot bar or shaft 30. The derrick 28 may be swung backwardly when not in use and during transportation to a substantially horizontal position and rest on the back end of the machine. The frame member 29 and the upright 4 are further braced by the bars 31 which are bolted to the frame member 29 and to the base members 1.

The advantage of making the walking beam 13 in the form shown is that the base or operated end is spread to receive the fulcrum post 10 between the walking beam members 13 and the operating end is contracted for causing the shoe 18 to run centrally over the well. The spread ends at the operated end form a brace to prevent lateral motion of the operating end of the walking

beam. The curvature of the shoe 18 on the part next to the chain serves to center the chain in a direction at right angles to the walking beam. The spreading of the walking beam members brings the support of the walking beam near the two ends of the pivot or supporting shaft 23 and thus prevents the load from being thrown on the central portion of the shaft 23.

10 Various changes in the several parts may be made without departing from my invention. The construction above set forth provides a machine with a dual capacity, either of which may be utilized at will.

15 What I claim, is,—

1. In a well-drilling machine, provided with a frame and a driving shaft provided with cranks and crank-pins; an upright fulcrum member rigid with said frame, a fulcrum mounted in said upright, a walking beam, means for pivotally connecting said walking beam to said fulcrum including plates under and against the walking beam and stirrups hung on said fulcrum and attached to said plates, a pivot shaft, and pitman bars pivotally connected to said pivot shaft and said cranks.

2. In a well drilling machine, provided with a frame and a driving shaft provided

with cranks and crank-pins; a walking beam, an upright bearing member rigid with said frame and projecting past said walking beam, a fulcrum carried in said upright, means for pivotally connecting said walking-beam to said fulcrum consisting of plates disposed under said beam and stirrups hung on said fulcrum and attached to said plates, a pivot shaft at the operated end of said walking beam, and means operatively connecting said walking-beam to said pivot-shaft consisting of adjustable bearings mounted on said shaft and pitman bars pivotally connected to said cranks and said bearings.

3. A well drilling machine having a walking beam and a fulcrum therefor, operating cranks, and means for pivotally connecting said cranks to said walking beam consisting of a pivot shaft for said walking beam, bearings mounted on said pivot shaft, pitman bars, plates attached to said pitman bars and pivotally connected to said bearings, and means for pivotally connecting said pitman bars to said cranks.

In testimony whereof, I set my hand, this 14th day of March, 1923.

HARRIS G. PARR.
